UNITED STATES PATENT OFFICE.

JOHN S. TOWNSEND, OF HARVEY, ILLINOIS, ASSIGNOR TO WHITING CORPORATION, OF HARVEY, ILLINOIS, A CORPORATION OF ILLINOIS.

LATERAL-SHIFTING MECHANISM FOR JACKS.

Application filed August 22, 1921. Serial No. 494,334.

To all whom it may concern:

Be it known that I, JOHN S. TOWNSEND, a citizen of the United States, residing at Harvey, in the county of Cook and State of Illinois, have invented a certain new and useful Improvement in Lateral-Shifting Mechanism for Jacks, of which the following is a specification.

This invention relates to jack mechanism for handling heavy loads of any kind. It is especially adapted and designed for and will be described as applied to railroad locomotives involving one, two or more hundred tons weight in the operation of lifting such a locomotive off from its wheels for repair work in the shop and for accurately replacing the locomotive on its wheels ready for normal use.

When a locomotive is removed from its wheels and in accordance with usual practice taken to another part of the shop for repair work and then after a time, moved back to its wheels, it is a practical certainty that the locomotive has shifted its position in a horizontal direction and that unless assisted by external mechanism it will not, on being lowered, register and fit with its wheels standing on the track ready to receive it. The object of this invention is to provide very satisfactory and efficient mechanism by which a heavy locomotive of the character described may, on being brought into proximity with its wheels, be shifted laterally until the frame of the engine is in register with and will accurately fit the wheel boxes belonging to the track wheels located in normal position on the track below the locomotive.

The invention consists in a readily constructible and easily operated mechanism for attaining the foregoing objects and in many features and details of construction which will be hereafter more fully set forth in the specification and claim.

Referring to the drawings in which like numerals designate the same parts throughout the several views—

Figure 1 is an elevation of a mechanism of this invention and locomotive resting thereon.

Figure 2 is a detailed sectional longitudinal elevation of the preferred form of lateral shifting mechanism.

Figure 3 is an end view taken at the left hand side of Fig. 2.

Figure 4 is a central sectional detail view on the line 4—4 of Fig. 2.

Figure 5 is a plan view, several parts being broken away, of the mechanism shown in Figure 2.

Figure 1 shows conventional track rails 10 on which the wheels 12 of the locomotive 14 or other excessively heavy object to be lifted travels. Conventionally arranged on opposite sides of the track 10 are vertical jack casings 16 having within them some conventional form of elevating mechanism not directly entering into this invention and therefore not shown adapted to raise or lower, as the case may be, horizontal cross beam 18 on which the locomotive rests after being removed from the wheels 12, it being understood that in lifting a locomotive two or more outfitts 16 and 18 are located at different points along the track 10 adjacent to the locomotive.

In lifting the locomotive 14 off from the wheels 12 it is essential that it be elevated high enough so that the conventional jaws 20 depending from the frame 22 and normally embracing the driving boxes 24 be lifted to some such position as shown in Fig. 1 in which the jaws 20 clear the driving boxes as shown and similarly it is necessary that on returning the engine to its normal position these jaws 20 engage the driving boxes and accurately enter between the flanges 26 provided on the driving boxes to receive the jaws and hold them in place.

In so lifting the locomotive the beam 18 engages the locomotive on a supporting member 28 which may be a permanent part or a temporary interposed blocking the only essential being that the beam 18 gets a hold on the locomotive at a point which will stand the strain so as to permit the beam when elevated to raise the locomotive or on reverse movement lower it as desired.

The problem solved by this invention is to provide means placed on and preferably detachably secured to the beam 18 and engaged by the locomotive supporting member 28 so that in the operation of lowering the locomotive onto its wheels, it may be easily given a movement lateral of the track 10, viz, a movement along beam 18 until the operator finds that the jaws 20 register with the wheel box 24 and that he can therefore lower the locomotive into normal position on the wheels 12.

The specific form of mechanism found most preferable for this purpose is shown in detail in Figures 2 to 5 inclusive. Two of these mechanisms are on the beam as shown in Figure 1, one under each of the parts 28 of the locomotive. They are alike except that they are positioned end for end so that an operator on each side of the locomotive may operate the one which is nearest to him.

The mechanism referred to includes the base member 32 adapted to rest on the beam 18, this base being the bottom of a box whose side walls are 66. Owing to the fact that different locomotives are of different widths between their supporting members 28, it is desirable that these plates 32 be selectively positionable and yet detachably securable to the beam. This in the particular case here illustrated is accomplished by providing on the under surface of the member 32 a plurality of recesses 34 adapted to selectively fit over different groups of knobs or pin-ends 36 on the top of the beam 18 and to be held in that position through the combination of these pins and the weight of the locomotive when it is applied as shown in Figure 1.

Rising from one end of the plate 32 is a shaft bearing block 38 perforated to receive the bearing member 40 of a screw shaft 56 provided with an integral flange 42 engaging one side of the block 38 and a fastening nut 44 screw threaded onto the shaft 46 and lockable in position by any suitable means as for instance a pin 48. In the mounting of the device suitable washers 50 are interposed as shown. The end of the shaft outside the nut is made in non-circular form 52 so that a socket wrench 54 may be applied to it as shown in Figure 1 whereby an operator on applying an ordinary ratchet wrench 56, to the end of this socket wrench may rotate the shaft bearing 40 in the block 38. The bearing is provided with oil thru a suitable oil hole 54. The bearing 40 described is an extension of screw threaded shaft 56 whose opposite end is preferably but not necessarily supported in a bearing 58 formed in an end plate 60 detachably secured in place by the lag screws 62 and 64 entering respectively the base 32 and the side walls 66 which rise from it and form a box about the screw shaft 56. These side walls 66 form the support or foundation for a finished metallic track 68 extending parallel with the central axis of the screw 56 and on opposite sides thereof.

Slidably mounted upon this track 68 is a load carrying cover plate 70 adapted to directly receive the locomotive carrying members 28 heretofore referred to. This cover plate 70 is adapted to slide along the tracks 68, even under heavy locomotive load, by reason of proper lubrication which is in the

case here illustrated attained by providing in the inner surface of the cover plate a plurality of oil chambers 72 preferably filled with oil retaining material such as felt 74 and freshly supplied with oil as needed thru oil ports 76.

Extending from the central bottom portion of the member 70 is a suitably constructed lug 80 which is perforated and screw threaded to receive the screw 56 as clearly shown in the drawing, the threads while in engagement with this member being suitably lubricated as, for instance by dropping oil down an oil passage 82 provided for the purpose.

In the operation of the device, the operator first places two base plates 32 in the proper position on the beam 18 in register with the pins 36 so that when the locomotive is brought in the parts 28 thereof will rest upon the plates 70. He then by operating the mechanism contained within the posts 16 positions the beam 18 to receive the locomotive. When the locomotive is brought in ready to be handled, he manipulates the lifting mechanism to raise beam 18 until the locomotive actually rests on and is carried by the plates 70. Two workmen are now assigned to the socket wrenches 54 on opposite sides of the locomotive and by working as near as may be in absolute unison, shift the locomotive horizontally as may be required on the beam 18 until the operator can see that the jaws 20 are in register with the wheel boxes 24, thereupon it is only necessary to operate the lowering mechanism to let the locomotive down into its proper normal position with reference to the wheels 12 whereupon the jack is removed from beneath the locomotive in the ordinary manner.

The socket wrenches 54 are made of considerable length merely for the reason that in most locomotives, the parts which can be carried by the device of this invention are usually so far under the locomotive that because of the obstruction offered by the locomotive cylinders 90 and other dependent parts it is not very practical for a man to apply a ratchet wrench directly to the ends 52 of the screw shaft 56.

One reason why it is necessary that the lateral shifting mechanism described shall be removable from the beam 18 lies in the fact that under well known practice, such for instance as that described in Hardy Patent No. 1,085,734, the beam 18 is, in initially admitting the locomotive to the lifting jack mechanism, lowered below the level of the rails 10 so that the wheels 12 pass across the beam or trackways 92 provided for the purpose, and under such conditions the wheels might injure or destroy the lateral shifting mechanism if they were then on the beam, particularly if in the position shown in Figure 1.

Having thus described my invention what I claim as new and desire to secure by Letters Patent is:

In mechanism for hoisting a locomotive,
5 a vertically reciprocable supporting beam, a pair of separated load receiving plates, carried by said beam, slow motion mechanism under each plate for moving the adjacent

plate along the beam, and means at the end of each plate, nearest its end of the beam, 10 adapted to be engaged by an operator at that end of the beam for operating the power means.

In witness whereof, I have hereunto subscribed my name.

JOHN S. TOWNSEND.
